METHOD OF EXHAUST AND APPARATUS
THEREFORHenry J. Nolte, Schenectady, N. Y., assignor to
General Electric Company, a corporation of
New York

Application April 14, 1930, Serial No. 444,082

1 Claim. (Cl. 250—27.5)

The present invention relates to electric discharge apparatus and more particularly to the process of manufacturing certain types of such apparatus.

5 In the manufacture of electric discharge tubes, it is necessary to remove occluded gases from the various metal parts within the envelope and especially from such members, as the anode, which become heated during operation. The 10 slightest amount of active gas given off by the anode or other metal member may impair the electrical characteristics of the tube and if sufficient gas is evolved, the resulting ionization under high voltage conditions may destroy the 15 tube.

In order to overcome these difficulties and to ensure the release of the last remnant of occluded gas, it has been the practice heretofore to heat the metal members during the evacuation 20 process by high frequency or otherwise, to a temperature somewhat higher than that attained in operation. This method gives satisfactory results in those cases where the heating of a given member can be effectively applied and 25 where the member is sufficiently rugged to withstand the combined simultaneous heating and evacuating effects. However, certain forms of electric discharge apparatus require members of hollow and delicate structure, as in the case of 30 electrodes which are cooled during operation by an externally applied medium such as water or air and must be thin in order to offer maximum ease of cooling.

The development of certain phases of the tube 35 art has necessitated tubes which require electrodes of special configuration whose shape must be rigidly maintained during the abnormal treatment given to the tube in manufacture. Furthermore, for reasons of minimizing electrical resistance and oxidation as well as for other considerations, the metal of an electrode is usually copper. When such members are heated and immersed in an attenuated atmosphere they are 40 subject to deformation of shape and sometimes 45 collapse if the full atmosphere is allowed access to the surface opposite to that being evacuated. Under these conditions the difference in pressure exerted on opposite sides of the heated hollow member constitutes a force tending to warp 50 the soft material.

An object of my invention is to improve the technique of removing occluded gases from electrodes and other metallic members of delicate construction contained in the envelope of electric 55 discharge devices. A more specific object is to

improve the method of and apparatus for removing occluded gases from electrodes of hollow and thin construction, the outer surfaces of the electrodes being subjected to relatively high vacuum under operating conditions or manufacturing conditions, or both. A more general object is to improve the manufacture of such devices. The invention will be better understood when reference is made to the following description and the accompanying drawing in which Fig. 1 is 60 a view partly in section and partly in elevation of a tube being evacuated in accordance with my invention; Fig. 2 shows the anode construction utilized in the tube illustrated in Fig. 1; Fig. 3 is a view partly in section of a cap arrangement fitted over one end of several exhaust conduits and useful in the evacuation of the anode interiors. 65

In Fig. 1, numeral 1 designates the glass envelope of a split anode magnetically controlled discharge device which employs two semicircular "mittens-like" anodes 2, arranged symmetrically about an axially disposed filament 3. A tube of this kind when connected in appropriate and known circuits and provided with electromagnetic coils 4 serves to generate oscillations of relatively large magnitude and of exceedingly short wave lengths for radio purposes. The anodes are constituted of thin copper, about 50 mils, and are peaned longitudinally at a position 70 midway of the width as indicated at 5 in such a manner as to form a continuous passage-way for a cooling medium along the upper, lower and end portions of each member. However, during 75 evacuation of the device and in accordance with my invention, the passageway is employed to withdraw air from the interior of the anode thereby partly or preferably entirely to equalize the pressure on both sides of the copper wall as 80 will be explained hereinafter. 85

The envelope 1 may be evacuated to the required degree of vacuum through a tube 6 which is connected to a fine pump (not shown but indicated), while the interior portion of each anode communicates with a rough pump (not shown but indicated) through one of the metal pipes or outlet conduits 7 and a metal hose 8. The adjacent metal pipe or inlet conduit 9 which leads to the other portion of the anode interior 100 is closed except for a small opening 10 drilled longitudinally through a thumb-screw 11. The thumb-screw is threaded into a metallic cylinder or cap 12 which embraces the pipe 9 and may be secured thereto by a set screw 13 or prefer- 105 110

ably by silver soldering. While the opening 10 may preclude the procurement of a high vacuum within the interior of each anode to off-set the effect of an equally high vacuum on the other side of the anode wall, the opening advantageously allows a small fast moving jet of air to sweep through the anode passages, thus preventing the metal from melting. The diminutiveness of each opening, however, still allows a vacuum to build up within the anode sufficiently high to preclude a substantial difference of pressure between the inner and outer surfaces of the anode wall.

During the evacuation, the filament 3 is energized and a high voltage applied between the filament and each anode 2 whereby the latter is heated by electron bombardment to a temperature sufficiently high to facilitate the removal of occluded gases. Inasmuch as the anode metal is hot during this operation and the copper wall is thin, the semi-circular anodes would normally tend to uncurl and straighten out if the atmosphere were allowed ready access to their interiors through the passage-ways during evacuation of the envelope.

However, in accordance with my invention, the pressure is maintained substantially equal on both sides of the anode wall and there is no unbalanced force of appreciable amount present to blow out or otherwise deform the shape of the anodes. The pump for maintaining the attenuated atmosphere within the anode interior is conveniently connected through the hose 8 to the metal tubing 7 by a rubber nipple 14 and it is found that the heat radiated by the anode during exhaust may deleteriously affect the rubber. In order to maintain the rubber cool thereby to retain its pliability, it is necessary to cool the ends of the metal tubing to which the nipple is attached. This is conveniently done by the use of water jackets 15 which have inlet and outlet

ports and are adapted closely to embrace the tubes 7 in a water-tight manner.

It will be evident that I have provided a convenient method and apparatus for removing the occluded gases from the metal of an electrode having a configuration and construction which would tend to deform when heated and when the pressures of the gaseous mediums on opposite sides of the electrode are substantially unequal. In the case of the type of electrode illustrated this deformation may take the form of unrolling or straightening out when the pressure in the interior of the electrode is considerably greater than that on the exterior thereof.

What I claim as new and desire to secure by Letters Patent of the United States:

An electric discharge device comprising an envelope adapted to be hermetically sealed and containing a hollow electrode from which the occluded gases are to be removed, said electrode being constituted of relatively thin metal and having a circular configuration which tends to straighten out when the electrode is heated and when subjected to considerably greater pressure in the interior than on the exterior thereof, said electrode being adapted to be heated to a temperature sufficiently high to facilitate the removal of the occluded gases, means for evacuating the interior of the envelope and simultaneously operating means for evacuating the interior of the hollow electrode whereby the pressure on opposite sides of the electrode are substantially equalized, and whereby the normal configuration of the electrode is maintained under heated conditions, said last mentioned means including inlet and outlet conduits which communicate with individual portions of the electrode interior, the inlet conduit being closed except for a small opening and the outlet being cooled by a fluid jacket.
